UNITED STATES PATENT OFFICE.

MAURICE C. RYPINSKI, OF YONKERS, NEW YORK.

DESIGN FOR A RADIOCABINET.

Application filed October 25, 1926. Serial No. 19,476. Term of patent 14 years.

To all whom it may concern:

Be it known that I, MAURICE C. RYPINSKI, a citizen of the United States of America, residing at Yonkers, county of Westchester, and State of New York, have invented a Radiocabinet, of which the following is a specification, reference being had to the accompanying drawing, forming part thereof. The figure is a perspective view of the radiocabinet showing my new design.

I claim:

The ornamental design for a radiocabinet as shown.

MAURICE C. RYPINSKI.
